UNITED STATES PATENT OFFICE.

ROSLA WASHINGTON WELCH, OF BALTIMORE, MARYLAND, ASSIGNOR, BY DIRECT AND MESNE ASSIGNMENTS, TO THE WELSH WHEAT CLEANING AND MANUFACTURING COMPANY OF BALTIMORE CITY.

WHEAT-SCOURING MACHINE.

SPECIFICATION forming part of Letters Patent No. 377,920, dated February 14, 1888.

Application filed November 27, 1886. Serial No. 220,052. (No model.)

To all whom it may concern:

Be it known that I, ROSIA WASHINGTON WELCH, of the city of Baltimore, in the State of Maryland, have invented certain Improvements in Wheat-Scouring Machines, of which the following is a specification.

In the modern systems of milling it is of the highest importance that the husk of the berry shall be left of its original strength and thickness, to the end that it may be removed in the preliminary milling operations in large flakes without being pulverized or broken. It is of importance, therefore, that the cleaning-machine shall act upon the berry with a gentle rubbing action and without a cutting, grinding, or percussive effect.

The aim of my invention is to provide a machine by which the wheat-berry may be effectually scoured and freed from the fuzzy portions without weakening the husk or fracturing the berry; and to this end it consists, essentially, in the combination of two vertical cylinders separated by an intermediate space, through which the wheat is permitted to descend slowly and driven in the same direction, but at different rates of speed, as will be hereinafter more fully described and explicitly claimed.

In the accompanying drawings, Figure 1 represents a vertical section of a machine having my improvement incorporated therein, showing the interior cylinder in elevation and partly broken away; Fig. 2, a horizontal cross-section of the same on line *xx*, Fig. 1.

Referring to the drawings, A represents a rigid frame-work, which may be of any suitable construction, provided with bearings which support a central vertical driving-shaft, B, carrying the vertical cylinder C. This cylinder is commonly made of a diameter of about twenty inches and of a length of thirty-six inches, more or less. It consists of a skeleton or other frame clothed, except at its extreme upper end, with woven-wire cloth, preferably of about twelve by fourteen mesh of steel wire. At its upper end, for a distance of four inches, more or less, the cylinder is encircled by a smooth metallic band, D, fixed securely thereto, and presenting a smooth surface to the de-

scending grain. The use of the smooth band D is advantageous, in that it permits the grain to enter more readily between the inner and outer cylinders. The outer surface of the cylinder C is encircled by a spiral rib, preferably a coarse wire, having a pitch of about four inches, and secured by staples or equivalent fastening devices. This rib trends downward in the direction in which the cylinder revolves, so that it exerts a lifting action upon the grain.

The inner cylinder is surrounded by a second and concentric cylinder, E, consisting of the skeleton frame clothed on its inner surface with wire-cloth similar to that on the inner cylinder, but without the spiral rib.

I construct the machine commonly with an annular space of half an inch (more or less) between the two cylinders. The outer cylinder is carried by arms or spokes radiating from a sleeve, F, which revolves loosely about the central driving-shaft, being supported by a separate bearing, as shown, or otherwise, the only requirement being that the two cylinders shall be free to revolve independently.

The driving-shaft B is provided with a driving-pulley, G, or other appropriate means for imparting motion thereto, and is also provided with a pinion, H, which imparts motion to a larger gear-wheel, I, on a small counter-shaft, J, which latter is in turn provided with a gear, L, engaging and driving a pinion, M, on the sleeve of the outer cylinder.

In action I commonly drive the inner cylinder at a speed of about five hundred revolutions per minute, and so proportion the gearing that the outer cylinder will be revolved at a speed of about seventy-five revolutions, the two cylinders turning in the same direction.

Around the outer cylinder, E, I place a stationary jacket or casing, O, and at the top of the machine, on the driving-shaft, I place a suction-fan, P, which communicates with the space between the jacket and the cylinder E. At the bottom of the machine I provide a discharge-spout, Q, having a valve, R, by which the flow of the material through the machine may be retarded in order to secure the proper action of the wheat-berries against each other and against the wire-cloth. At the top of the

machine I provide a feed-hopper, as shown, or other equivalent means for delivering the grain between the two cylinders.

In operating the machine care is to be taken 5 to see that the space between the two cylinders is completely filled with grain, and that the descent of this grain is retarded so that the grain is retained until brought to the proper condition.

10 The revolution of the outer cylinder causes the grain to be urged outward by the centrifugal force strongly against the surface of the cylinder, and also causes the wheat-berries to bear forcibly against each other. The revolution of the inner cylinder at a different speed 15 serves to agitate the grain, its rib acting to lift and turn the grain and keep the same in constant motion, so that every berry is brought in contact as to every portion of its surface 20 with the wire-cloth and with the adjacent berries. The result of this action is a thorough cleansing of the berry without the slightest injury thereto.

I am aware that machines have been constructed 25 with a stationary outer and a rotary inner cylinder, and also that machines have been constructed in various forms with two concentric cylinders revolving in opposite directions.

30 The advantage of my invention lies mainly in the fact that by the revolution of the two cylinders in one direction at differential speeds I am enabled to drive the cylinder at a speed sufficiently high to develop a strong 35 centrifugal action and a correspondingly forcible pressure of the grain in an outward direction, without, on the other hand, developing that violent scouring action which would result from the revolution of the cylinders in 40 different directions.

I am aware that smut-machines, flour-bolts, and other machines have been constructed 45 with concentric reels and drums, and that gearing has been applied to revolve these drums, in some cases in the same and in other cases in opposite directions; but I believe myself to be the first to produce a wheat-cleaning machine in which two cylinders covered with wire-cloth have been driven in the same 50 direction at different speeds; and in practice I

find that when thus constructed the machine operates to effectually clean the grain without cutting or weakening its husk, and that the results secured are better than those which I have been able to obtain under any other construction. When the machine is in operation 55 and the outer cylinder driven at a high speed, the centrifugal force acts to throw and hold the grain against its inner surface, subject to the action of the inner cylinder, the result being that the berries are rubbed with a gentle pressure upon each other and upon the smooth surfaces of the wire-cloth in a manner peculiarly efficacious as regards the end in view. 60

I do not claim, broadly, herein the combination of two concentric cylinders, the inner one of which is provided with ribs trending in a forward direction, such combination forming the subject-matter of a prior application filed by me on the 9th day of July 1886, No. 207,597, 65 the outer cylinder in that application being, however, a stationary instead of a revolving cylinder, as herein claimed. Neither do I claim herein the combination of an external cylinder with a surrounding jacket and an exhaust-fan. 70

Having thus described my invention, what I claim is—

1. In a wheat cleaning machine, the combination of an upright inner cylinder clothed 80 with wire-cloth and provided with the spiral lifting-rib, the outer concentric cylinder, also clothed with wire-cloth, and mechanism, substantially as described, for revolving said cylinders in one and the same direction at different 85 speeds.

2. In a wheat-scouring machine, the combination of the outer revoluble cylinder and the inner revoluble cylinder, the latter provided at its upper end with the smooth surface D 90 and with the wire-cloth covering and the spiral rib.

In testimony whereof I hereunto set my hand, this 15th day of November, 1886, in the presence of two attesting witnesses.

ROSLA WASHINGTON WELCH.
